(57) **CLAIM**

The ornamental design for an "X-ray scanner", as shown and described.

DESCRIPTION

FIG. 1 is a perspective view of an X-ray scanner according to the invention;

FIG. 2 is an alternative perspective view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view thereof; and,

FIG. 8 is a rear elevational view thereof.

The broken lines in the drawing views are included for the purpose of illustrating portions of the X-ray scanner that form no part of the claimed design.
